(57) **CLAIM**

The ornamental design for a splash block as shown and described.

DESCRIPTION

FIG. 1 is a perspective view of a splash block showing the claimed design.

FIG. 2 is a top view of the splash block of FIG. 1.

FIG. 3 is a bottom view of the splash block of FIG. 1.

FIG. 4 is a rear side view of the splash block of FIG. 1.

FIG. 5 is a front side view of the splash block of FIG. 1; and, FIG. 6 is a lateral side view of the splash block of FIG. 1. The opposing lateral side is a mirror image of the lateral side shown in FIG. 6.

The broken lines in the figures depict portions of the article that form no part of the claimed design.

1 Claim, 6 Drawing Sheets
